CARTRIDGE FOR RECORDING TAPE

Donald D. Merry, Westland, and Carl J. Fuhst, Brighton, Mich., assignors to Quixonic, Inc., Plymouth, Mich., a corporation of Delaware

Continuation-in-part of design application Ser. No. 7,017, May 8, 1967. This application Oct. 18, 1967, Ser. No. 9,303

Term of patent 14 years

(Cl. D26—14)

Fig. 1

Fig. 2

Fig. 3

FIGURE 1 is a perspective view of the cartridge for recording tape and illustrating our new design;

FIGURE 2 is a side elevation as seen from the right of FIGURE 1;

FIGURE 3 is an elevation as seen from the distal end of FIGURE 1;

FIGURE 4 is a perspective view of a modified embodiment of the cartridge shown in FIGURE 1;

FIGURE 5 is a side elevation as seen from the distal end of FIGURE 4; and

FIGURE 6 is a perspective view of a further modified embodiment of the cartridge illustrated in FIGURE 1.

The unshown rear portion of all of the embodiments of the cartridge are substantially plain and unornamented. The characteristic feature of our design resides in the generally rectangular cartridge having one end thereof curved downwardly toward the generally flat back.

This application is a continuation-in-part of design application 7,017, filed May 8, 1967, and now abandoned.

We claim:

The ornamental design for a cartridge for recording tape, substantially as shown and described.
